Re. 20,528

FRUIT JUICE EXTRACTOR

Original Filed May 17, 1930

FIG. 1.

UNITED STATES PATENT OFFICE

20,528

FRUIT JUICE EXTRACTOR

Edward T. Keenan, Frostproof, Fla.

Original No. 1,982,741, dated December 4, 1934,
Serial No. 453,396, May 17, 1930. Application
for reissue May 28, 1936, Serial No. 82,446

12 Claims. (Cl. 146—3)

This invention relates to an improvement in a method of extracting citrus juices by means of compressed air or other gases, or by means of a vacuum.

5 The use of citrus fruit juice as a beverage is becoming more popular, and methods are and have been developed for the placing of this fruit juice in cans or bottles, which will amount to about one-half the volume of the fresh fruit 10 produced.

To extract this fruit juice from the fresh fruit has been a most expensive and unsatisfactory operation in connection with the problem. Heretofore, this has been accomplished by cutting the 15 fruit in half and either squeezing the sections or holding the halves against a revolving burr to remove the juice and pulp from the hulls or skins of the fruit.

It is the object of this invention to substantially 20 simplify and improve this operation by removing the juice through the use of compressed air or other gases, or even by the use of a vacuum, acting on the sections of the fruit to force the juice sacs from the skins and into a suitable receptacle.

In the accompanying drawing:

Fig. 1 is a top plan view of an apparatus which may be used to carry out the invention; and

Fig. 2 is a vertical sectional view therethrough.

30 A table is represented by the numeral 1, having a recess or seat 2 in the surface thereof, in which is mounted a plate 3 secured in place by set screws 4. The plate 3 is provided with a series of apertures 5 therethrough and so arranged as to be disposed under the half of a section of grapefruit, orange or the like, which may be placed over the plate 3.

A casing 6 is secured beneath the plate 3 by means of set screws 7, or the like, and this casing 40 6 has a chamber 8 therein communicating with the openings 5 in the plate 3. One or more pipes 9 extend to the chamber 8 for supplying air thereto, and if desired baffles 10 may be disposed in the chamber immediately above the 45 openings of the pipes 9.

The casing 6 has a central opening 11 therethrough registering with a central opening 12 in the plate 3, through which the juice sacs and portions of the pulp may be removed there- 50 through and forced downward into a suitable receptacle.

In the operation of the invention, the fruit, such as orange, grapefruit or the like, may be cut in half along a line corresponding with the 55 equator, and the sections may be placed on a

suitable belt conveyor, designated generally by the numeral 13, in Fig. 1, which travels along a table beside or in line with the plate 3. The sections of fruit are transferred from the belt to a position over the openings 5 in the plate 3, and these sections are designated generally by the 5 numeral 14.

At the same time that the sections 14 are placed on the plate 3 over the openings 5, air will be automatically turned on through the pipe or pipes 9, the chamber 8 and the openings 5, forcing its way out through the openings in jets and into and about the juice sacs of the fruit, these jets of air cutting the juice sacs from the skin and blowing them down through the openings 11 and 12, where 15 they are received in a suitable receptacle, such as a bucket or the like.

The sections 14 should preferably be rotated either manually or mechanically so as to bring different points in line over the openings 5 and 20 to aid in cutting the juice sacs from the skins. After the juice sacs have been effectively removed from the skins, the latter are removed 25 from the plate, which automatically cuts off the compressed air or other gases used until another section is in place.

The operation may be entirely automatic and serves as an effective means for removing the juice sacs from the sections of the citrus fruit.

While compressed air is preferable, yet other 30 gases under pressure may be used instead, as found desirable, or a vacuum may be used in place of the compressed air or gases with this improved construction with slight alteration in the plate.

If desired, the air may be supplied through a 35 revolving burr of the usual kind, the air jets forcing the juice sacs through openings in the plate.

I claim:

1. A method of extracting juice sacs or the like from citrus fruit, comprising subjecting the 40 interior of the fruit to the action of air jets under a pressure greater than atmospheric to force the juice sacs from the skins.

2. A method of removing the juice or pulp from sections of citrus fruit or the like, comprising 45 subjecting the interior of the fruit to the action of a jet of compressed gas to force the juice and pulp from the skins.

3. A method of removing portions from a half section of citrus fruit or the like comprising sub- 50 jecting the open side of the section to one or more jets of compressed gaseous medium.

4. A method of removing juice and pulp from the interior of a half section of citrus fruit or the like comprising directing one or more jets of 55

gas under pressure against the open side of the section.

5 5. A device of the character described comprising a plate having openings therein to receive a section of citrus fruit, and means for forcing jets of fluid from said openings to sever portions of the interior of the fruit from the skins thereof.

10 6. A device of the character described comprising a plate having openings therein to receive a section of citrus fruit or the like, and to apply a fluid action thereto to remove the juice sacs from the skins, said plate having an opening therein to be disposed approximately at the center of the fruit section to receive the juice sacs therefrom.

15 7. A device of the character described comprising a plate having openings therein to receive a section of citrus fruit or the like, and to apply a fluid action thereto to remove the juice sacs from the skins, said plate having an opening therein to be disposed approximately at the center of the fruit section to receive the juice sacs therefrom, and a casing secured beneath the plate and having a chamber therein communicating with the openings in the plate.

20 25 8. In a device of the character described, the combination with a table having a recess in the surface thereof, of a plate seated in said recess and having a plurality of constricted orifices in the surface thereof to be disposed beneath a citrus fruit section, said plate having an enlarged recess approximately at the center of the orifices for the removal of portions of the fruit section, a chamber disposed beneath and communicating

with the orifices, and means for securing said chamber in place beneath the plate.

9. A fruit juice extractor comprising a nozzle having one or more openings therein and adapted to receive the open side of a half section of citrus fruit or the like, and means for forcing gas under pressure through said opening or openings in the form of jets which impinge against the open side of the fruit to remove portions of the interior from the skins thereof. 5

10 10. A fruit juice extractor comprising a nozzle having one or more openings therein and adapted to receive the open side of a half section of citrus fruit or the like, and means for forcing gas under pressure through said opening or openings in the form of jets which impinge against the open side of the fruit to remove portions of the interior from the skins thereof, said nozzle having an enlarged central exit opening to receive the removed portions. 15

11. A process for removing juice from succulent fruit comprising forming an opening in the covering of the fruit and impinging an air current against the succulent core to remove same through the opening of the covering. 20

12. A process of removing juice from a severed portion of citrus fruit, the cut face of said severed portion being flat, comprising impinging one or more fluid jets approximately perpendicularly against said flat face, said jet or jets being of sufficient force to disrupt the juice cells and remove the juice from the fruit portion. 30
